BENJAMIN R. COLE, OF BUFFALO, NEW YORK.

Letters Patent No. 98,149, dated December 21, 1869.

IMPROVEMENT IN OPERATING-DEVICES FOR WATER-CLOSETS.

The Schedule referred to in these Letters Patent and making part of the same

To all whom it may concern:

Be it known that I, BENJAMIN R. COLE, of the city of Buffalo, in the county of Erie, and State of New York, have invented a certain new and useful Improvement in Self-Acting Water-Closets; and I do hereby declare that the following is a full and exact description thereof, reference being had to the accompanying drawings, making part of this specification.

Two methods of operating the valves of water-closets are in ordinary use, viz, by pressure on the seat, and by means of a "pull," as it is termed, arranged at one side. Both of these methods are found objectionable. The former, on account of the great waste of water, as the valve remains open during the whole of the time the seat is occupied; the latter, on account of the liability of the party using the closet failing, either from ignorance, indifference, or forgetfulness, to properly operate the "pull."

The object of my improvement is to obviate these objections, by preventing, on the one hand, all unnecessary waste of water, and, on the other hand, insuring the proper opening of the valve after every use of the closet.

The invention consists in connecting the lever, which actuates the pan and valve, with a hinged foot-board, in such a manner that the weight of the occupant of the closet, as he rises from the seat, will depress the foot-board and open the valve, the lever and connecting-rod being so weighted and adjusted that the pressure of the occupant's feet, while sitting, will be insufficient to open the valve.

In the accompanying drawings—

Figure I is a front elevation of a water-closet, with the casing removed to exhibit the mechanism.

Figure II is a similar end elevation.

Like letters refer to like parts in each of the figures.

A is the ordinary seat of a water-closet, and B, the bowl or basin thereof.

C is the lever employed in actuating the pan and valve, having its fulcrum at e, the valve being shown at D.

The construction and arrangement of this valve, and the manner of connecting it with the lever, are different in the different devices patented and in use, the construction and operation of which are well un-

derstood, to all of which my improvement is applicable.

C' is a short arm or extension of the lever;

E is a foot-board, hinged in front; and

F, a pull-rod connecting the back and free edge of this board with the end of the extension-arm C'.

Various methods for uniting this connecting-rod with the lever and foot-board may be employed; that shown being an arm or hook g, projecting from the foot-board and engaging with an adjustable eye-nut, h, at the lower end of the rod F, while the upper end of the latter hooks into a hole, i, in the end of the lever. The adjustable nut h enables the connecting-rod to be readily adapted to the closet to which it is to be applied.

The amount of pressure required to depress the foot-board may be regulated in two ways: either by adjusting the hooks at the upper end of the pull-rod F, in the holes i i, so as to increase or lessen the distance of the connection from the fulcrum e, or by means of an adjustable weight, J, on the long arm of the lever, or by both combined.

Instead of arranging the connecting-rod F, as before described, it may be arranged on the opposite side of the fulcrum of the lever, with a pedal-lever underneath its lower end, by which the rod is pushed upward under the long arm, producing obviously the same effect as when it operates as a pull, at the end of arm C'.

The other advantages of my improvement, in addition to those before enumerated, are its cheapness and the facility with which it can be adapted to the various water-closets already in use.

I do not claim any of the details of this apparatus; but what I claim, is—

The combination of the lever C C', and pan and valve of a water-closet actuated thereby, with foot-board E, hinged in front, and the adjustable connecting-rod F, when arranged and operating substantially as and for the purpose hereinbefore set forth.

BENJ. R. COLE.
